UNITED STATES PATENT OFFICE.

JUDGE MARION BEDWELL, OF FAYETTEVILLE, TENNESSEE.

ACETYLENE-GAS GENERATOR.

1,199,863.

Specification of Letters Patent.

Patented Oct. 3, 1916.

Application filed January 4, 1916. Serial No. 70,106.

To all whom it may concern:

Be it known that I, JUDGE M. BEDWELL, a citizen of the United States, residing at Fayetteville, in the county of Lincoln and State of Tennessee, have invented new and 5 useful Improvements in Acetylene-Gas Generators, of which the following is a specification.

This invention is an improved acetylene gas generator, the object of the invention being to provide an improved machine of this kind which is cheap and simple in construction, is strong and durable, is automatic in operation and which can be recharged while 10 the lights are burning and without affecting 15 the lights and also without waste of gas.

The invention consists in the construction, combination and arrangement of devices hereinafter described and claimed.

In the accompanying drawings: Figure 1 20 is a vertical central sectional view of an acetylene gas generator constructed in accordance with my invention and showing the same with the bell and carbid container lowered. Fig. 2 is a sectional view of a detail.

The usual tank is indicated at 1 and the gas reservoir bell at 2. Standards 1^a rise from the upper end of the tank and serve to 30 hold the bell straight, when the machine is charged with gas and the bell is raised. In accordance with my invention, I provide a container 3 which is arranged in the center of the gas reservoir bell, extends downwardly therein for a suitable distance from 35 the top of the bell and also projects slightly above the top of the bell and is open at its upper end. At its lower end or bottom, the said container is perforated as at 4. An inner wall 5 rises from the bottom of the 40 container for a suitable height and is spaced from the outer wall of the container. That portion of the bottom between the inner wall and the outer wall is imperforate so that the inner wall is arranged to form a seal chamber 6. This seal chamber receives the lower 45 end of a sealing bell 7, which is secured in the container 3 by a bar or other suitable device 8 which bears on the top of said sealing bell and is here shown as passing through 50 openings near the upper end of the container. A carbid magazine or holder 9 is arranged in and removable from the container 3 and bears on the upper end of the inner wall 5. Said carbid magazine or 55 holder is open at its upper end, is perforated

at its bottom and lower portion as at 10 and is provided with a centrally arranged guide tube 11. The bottom has an opening and is also provided with a closure therefor which 60 closure is hinged at one side as at 10^a to facilitate emptying of the contents of the carbid holder, when required. A U-shaped gas distributing pipe 12 is arranged in the tank 1 with its vertical intake arm 13 passing up through openings in the bottom of the container 3 and carbid magazine or holder 9 and also through the guide pipe 11 of the carbid holder and is open at its upper end in the upper portion of the sealing bell 7. The vertical outlet arm 14 of said gas distributing pipe is arranged against and under the gas reservoir bell 2 and is provided with a check valve 15. The arm 14 of the pipe 12 is provided with a depending 75 U-shaped trap 14^a to receive such water as condenses from the gas in said pipe, and to keep the pipe air-tight.

I also provide a U-shaped gas service pipe 16 which has its vertical intake arm 17 arranged in the gas reservoir bell and its outer, discharge arm 18 arranged without the tank 1, the said pipe passing through one side of the tank at the bottom thereof as at 19 and being provided with a downwardly extending drain arm 20 for the reception of the water condensed from the gas. A suitable gas purifier 21 is arranged in communication with the discharge arm 18 of the gas service pipe.

A suitable quantity of water is kept in the tank 1 and from time to time as required the holder or magazine 9 is charged with carbid. This may be easily done by first removing the sealing bell 7. When the sealing bell is replaced and fastened by the element 8 its lower portion, being arranged in the seal chamber 6 is effectually sealed to prevent escape of gas. When the gas reservoir bell 2 moves downwardly the lower portion of the container 3 and the lower portion of the carbid holder 9 is submerged so that water is supplied to the carbid and gas is generated. The pressure of the gas then moves the gas reservoir bell together with the container, sealing bell and carbid holder up and as the gas is expanded and consumed the bell slowly settles until the carbid is again brought in contact with the water and so on, the generator acting automatically as will be understood. The check valve 15 holds the gas in the generator and

allows the light to keep burning while recharging the generator with carbid and without admitting air to the gas reservoir bell.

5 To prevent undue gas pressure in the apparatus, I provide a counterweight 22 which is connected to the upper end of the container 3 and hence to the gas reservoir bell by a cord 23, which cord passes over suitable pulleys 24, the weight being suspended by the cord and being arranged at one side of the apparatus. The weight although not so heavy, as the bell and attachments carried by the bell, tends to exert an upward 10 pull on the bell so that the latter will rise under moderate gas pressure. The weight may be varied to enable any desired gas pressure to be obtained and may consist of detachable members 25 arranged on a 15 central rod 26.

Having thus described my invention, I claim:—

1. An acetylene gas generator comprising a water tank, a gas distributing pipe having 25 a vertical intake arm arranged in said tank, a gas reservoir bell in said tank, a container carried by and depending from the top of the bell, said container being open at its upper end, and being provided with a bottom having a guide opening through which said intake arm of the distributing pipe extends, the bottom being also provided with a perforated portion, an inner wall on the bottom of the container arranged around 30 the perforated portion, spaced from the outer wall thereof, arranged around the perforated portion of the bottom so that a seal chamber is formed between said inner and outer walls; a sealing bell movable in 35 the container and sealed in the seal chamber thereof, means to detachably secure the sealing bell in place, and a carbide holder arranged in the container, bearing directly 40

on and supported by said inner wall of the container and having openings in the bottom within the periphery of the inner wall for the reception of water when submerged and arranged in the container. 45

2. An acetylene generator comprising a water tank, a gas distributing pipe having 50 a vertical intake arm arranged in said tank, a gas reservoir bell in said tank, a container carried by and depending from the top of the bell, said container being open at its upper end and being provided with a bottom having a guide opening through which said intake arm of the distributing pipe extends, the bottom being also provided with a perforated portion; an inner wall on the bottom of the container spaced from 55 the outer wall thereof, arranged around the perforated portion of the bottom so that a sealing chamber is formed between said inner and outer walls, a sealing bell movable in the container and sealed in the sealing 60 chamber thereof, means to detachably secure the sealing bell in place, and a carbide holder arranged in the container, bearing directly on and supported by said inner wall of the container and having openings in the bottom within the periphery of the inner wall for the reception of water when submerged 65 and arranged in the container, said carbide holder also having a guide tube into which the intake arm of the distributing pipe extends and being further provided with a perforated hinged closure for its bottom 70 openings, said hinged closure also having an opening through which the intake arm of the distributing pipe extends. 75

In testimony whereof I affix my signature in presence of two witnesses.

JUDGE MARION BEDWELL.
